CLAIM

The ornamental design for a footwear sole, as shown and described.

DESCRIPTION

FIG. 1 is a front perspective view showing my new design for a footwear sole;

FIG. 2 is a left side view of the footwear sole of FIG. 1;

FIG. 3 is a right side view of the footwear sole of FIG. 1;

FIG. 4 is a front view of the footwear sole of FIG. 1;

FIG. 5 is a back view of the footwear sole of FIG. 1;

FIG. 6 is a top view of the footwear sole of FIG. 1; and,

FIG. 7 is a bottom view of the footwear sole of FIG. 1.

The broken line showing is for illustrative purposes only, and depicts environmental structure and portions of the footwear sole that form no part of the claimed design.

1 Claim, 7 Drawing Sheets
